Fig. 3

Fig. 4

Fig. 5

Fig. 6

Fig. 7

FIG. 1 is a perspective view of an adapter for mounting speed reducers on conveyors, embodying the present design;

FIG. 2 is a perspective view of the end opposite that shown in FIG. 1;

FIG. 3 is an elevational view of the end seen in FIG. 1;

FIG. 4 is a side elevational view of the adapter;

FIG. 5 is a transverse cross-sectional view of the adapter, the section being taken on line 5—5 of FIG. 4;

FIG. 6 is a side elevational view; and

FIG. 7 is an axial cross-sectional view of the adapter, the section being taken on line 7—7 of FIG. 3.

I claim:

The ornamental design for an adapter for mounting speed reducers, as shown.
